United States Patent [19]

Houck et al.

[11] Patent Number: Des. 409,934

[45] Date of Patent: ** May 18, 1999

[54] **MODULAR ELECTRIC UTILITY METER SENSOR MODULE**

[75] Inventors: **Thomas P. Houck; Philip L. Jackson**, both of West Lafayette; **John T. Voisine; Charles Bolam**, both of Lafayette, all of Ind.

[73] Assignee: **Siemens Power Transmission & Distribution, LLC**, Wendell, N.C.

[**] Term: **14 Years**

[21] Appl. No.: **29/081,398**

[22] Filed: **Dec. 31, 1997**

[51] LOC (6) Cl. **10-04**

[52] U.S. Cl. **D10/103; D10/100**

[57] CLAIM

The ornamental design for a modular electric utility meter sensor module, as shown and described.

DESCRIPTION

FIG. 1 is a right front perspective view of our new design for a modular electric utility meter sensor module;

FIG. 2 is a back elevational view of the modular electric utility meter sensor module of FIG. 1;

FIG. 3 is a right side view of the modular electric utility meter sensor module of FIG. 1;

FIG. 4 is a left side view of the modular electric utility meter sensor module of FIG. 1;

FIG. 5 is a front view of the modular electric utility meter sensor module of FIG. 1;

FIG. 6 is a rear view of the modular electric meter sensor module of FIG. 1; and,

FIG. 7 is a top elevational view of the modular electric utility meter sensor module of FIG. 1.

In FIGS. 1 through 7, the broken lines showing of portions of the surface detail, the bottom support structures, the security interlocks receptacles, and the current blades, is for illustrative purposes only and forms no part of the claimed design.
